UNITED STATES PATENT OFFICE.

OLIVER McCARTHY, OF MERIDEN, CONNECTICUT, ASSIGNOR TO THE MERIDEN BRITANNIA COMPANY, OF SAME PLACE.

DESIGN FOR A COFFIN-PLATE.

SPECIFICATION forming part of **Design No. 22,217**, dated **February 14, 1893.**

Application filed September 29, 1892. Serial No. 447,348. Term of patent 7 years.

To all whom it may concern:

Be it known that I, OLIVER McCARTHY, of Meriden, in the county of New Haven and State of Connecticut, have invented a new 5 Design for a Coffin-Plate; and I do hereby declare the following, when taken in connection with accompanying drawing and the letters of reference marked thereon, to be a full, clear, and exact description of the same, and which 10 said drawing constitutes part of this specification, and represents a face view of a coffin-plate illustrating my design.

This invention relates to a design for name-plate for coffins, and consists in the orna- 15 mentation as shown in the accompanying illustration.

The sides of the plate recede from the panel, and so as to represent a border around the panel. On the surface of this border at the 20 sides and ends, is the representation of festoons of flowers, the said festoons appearing

to be suspended near the edge of the panel by ribbon knots, and with depending flowers at the ends of the said festoons. On each end of the plate is a like representation of 25 festoons, and at each side the festoons is the representation of a shell ornament, but the essential feature of the design is the representation of festoons suspended from knots on opposite sides of the panel. 30

I claim—

The design for coffin-plate as herein de- 35 scribed and shown in the accompanying draw- ing.

In testimony whereof I have signed this 35 specification in the presence of two subscriv- ing witnesses.

OLIVER McCARTHY.
